LAPPING MACHINE

Herbert S. Indge, Westboro, Mass., assignor to
Norton Company, Worcester, Mass., a corpora-
tion of Massachusetts

Application March 7, 1944, Serial No. 525,381

8 Claims. (Cl. 51—118)

This invention relates to lapping machines, and more particularly to a lapping machine for simultaneously lapping the opposed faces of a work piece.

One object of the invention is to make a thoroughly practical lapping machine for simultaneously lapping the opposed faces of a plurality of work pieces. Another object of the invention is to provide a lapping machine having two opposed lapping elements and work holders which are relatively rotated and revolved between said lapping elements for simultaneously lapping the opposed faces on a plurality of relatively thin work pieces.

A further object of the invention is to provide a lapping machine having a pair of opposed lapping wheels and a plurality of work cages or holders therebetween which are rotated and revolved during a lapping operation with a mechanism for imparting a relative reciprocatory motion between the cages and the cage driving mechanism. Other objects will be in part obvious or in part pointed out hereinafter.

The invention accordingly consists in the features of construction, combinations of elements, and arrangements of parts, as will be exemplified in the structure to be hereinafter described and the scope of the application of which will be indicated in the following claims.

In the accompanying drawings, in which is shown one of various possible embodiments of the mechanical features of this invention,

Fig. 1 is a vertical sectional view through the lapping elements and the work holder and cage driving and reciprocating mechanism;

Fig. 2 is a fragmentary side elevation, on a reduced scale, of a lapping machine embodying this invention;

Fig. 3 is a fragmentary plan view, on a reduced scale, taken approximately on the line 3—3 of Fig. 1, with the upper lap removed;

Fig. 4 is a fragmentary sectional view, taken approximately on the line 4—4 of Fig. 1, showing the gear train for driving the fluid pump and also the cage driving mechanism;

Fig. 5 is a fragmentary sectional view, on an enlarged scale, showing the floating connection between the upper lap and its supporting spindle; and

Fig. 6 is a fragmentary sectional view, taken approximately on the line 6—6 of Fig. 5.

A lapping machine has been illustrated in the drawings, comprising a base 10 which serves as a support for a pair of opposed lapping wheels 11 and 12 having opposed plane lapping faces.

In the preferred construction the upper lapping wheel 12 is supported by a floating connection at the lower end of a vertically movable spindle 13. The spindle 13 is slidably supported within a frame 14 which is formed integral with an arm 15. The arm 15 is adjustably supported on a vertical column 16 which is in turn fixed relative to the base 10. The arm 15 is arranged so that it may be adjusted vertically on the column 16 by means of a locating collar 17 which is clamped to the column 16 by means of a clamping bolt 18. The arm 15 is preferably arranged so that it may be swung to an inoperative position to facilitate loading of work holders and work pieces in the machine.

As shown in Fig. 2, the lower portion of the arm 15 is provided with a slot 19. A stud 20 is fixedly mounted on the collar 17 and serves to limit the swinging movement of the arm 15 and the upper lapping wheel 12. The spindle 13 is provided with a rack 21 which meshes with a rotatable pinion (not shown). The lapping wheel 12 and its supporting spindle 13 may be raised or lowered by means of a spoked manually operable wheel 22 which is fixedly connected to the pinion (not shown). The hand wheel 22 and the pinion (not shown) are both fixedly mounted on a rotatable shaft 23. The shaft 23 is also provided with a ratchet wheel 24, and a ratchet pawl 25 is pivotally mounted on the arm 15 so that the upper lapping wheel 12 may be readily raised to an inoperative position and held in this position by means of the pawl 25 and the ratchet wheel 24. The construction above described is standard and well known and has been used in lapping machines for many years. For further details of this construction, reference may be had to the expired U. S. patent to H. S. Indge No. 1,610,527, dated December 14, 1926.

The upper lapping wheel 12 is provided with a floating connection so that the lapping wheel 12 may readily align itself with the work pieces carried by the work holders to be hereinafter described. The lower end of the spindle 13 is provided with a partial spherical surface 26 which is formed integral with a reduced portion 27 of the spindle 13. The spherical surface 26 is arranged to slide within a cylindrical aperture 28 formed in a spider 29 which supports the upper lapping wheel 12. The lower end of the reduced portion 27 of the spindle 13 is provided with a thrust collar 30 which is fixedly mounted thereon by means of a nut 31. A clearance is provided between the lower surface of the spider 29 and the thrust collar 30 which serves to facilitate

tate a free aligning movement of the upper lapping wheel 12 and its supporting spider 29 relative to the work pieces to be lapped. In order that the upper lapping wheel 12 and its supporting spider 29 may be held against rotation, a pair of diametrically opposed studs 32 and 33 project outwardly from the spherical surface 26 on diametrically opposite sides thereof. The studs 32 and 33 are arranged to slide freely within keyways 34 and 35 which are formed on diametrically opposite sides of the aperture 28 in the spider 29. It will be readily apparent from the foregoing disclosure that the upper lapping wheel 12 is free to float relative to its supporting spindle so that its lapping surface may align itself 15 with the upper faces of the work pieces to be lapped.

The lower lapping wheel 11 is supported on a spider 40 which is fixedly mounted on the upper end of a vertically arranged cylindrical sleeve 41. The sleeve 41 is slidably supported in a bearing surface 42 formed in a housing 43 which is fixedly mounted on the base 10. The sleeve 41 is arranged so that it may be reciprocated in an axial direction by means of a reciprocating mechanism 20 to be hereinafter described.

The lapping machine is provided with a plurality of work holders 45, 46, 47 and 48, each of which is provided with a plurality of work receiving apertures 49. This machine is particularly adapted for lapping work pieces of relatively thin cross section and the work holders 45 are, therefore, relatively thin disks, being in some cases only a few thousandths of an inch in thickness. These work cages may be formed of a resinoid material, such as Micarta. The periphery of the work holders 45, 46 and 47 is formed as a gear by means of which a combined rotary and revolving movement may be imparted to the work holders and work pieces while in an operating position between the lapping wheels 11 and 12.

In order to impart a rotary and revolving movement to the work holders 45, 46, 47 and 48, a central gear 50 is fixedly mounted on the upper end of a rotatable shaft 51. The gear 50 is arranged to mesh with the gear teeth formed on the work cages. A ring gear 52 having internal gear teeth formed thereon is arranged concentric with the gear 50 and the lapping wheels 11 and 12 and meshes with the gear teeth formed on the work holders 45, 46, 47 and 48. The ring gear 52 is supported on a rotatable spider 53 which is rotatably supported by anti-friction bearings 54 and 55 which are in turn supported on the housing 43.

The shaft 51 is rotatably supported by an anti-friction bearing 58 carried by the housing 43 and also by bearings 56 and 57 which are carried by the sleeve 41.

A driving mechanism is provided for imparting a relative rotary motion to the gear 50 and the ring gear 52 which comprises a shaft 60 which is journaled in suitable bearings (not shown) in the base 10. The shaft 60 may be driven either by a belt driving mechanism, such as shown in the expired patent to Indge above referred to, or may be motor driven, as desired. A worm 61 is fixedly mounted on the shaft 60 and is arranged to mesh with a worm gear 62 which is keyed to the lower end of the shaft 51. It will be readily apparent from the foregoing disclosure that a rotary motion of the shaft 60 will be imparted through the worm 61 and the worm gear 62 to rotate the shaft 51 and the gear 50.

A driving mechanism is provided for the ring 75

gear 52 comprising a gear 63 which is fixedly mounted on a hub formed integral with the worm gear 62. The gear 63 meshes with an idler gear 64 (Fig. 4) which is rotatably mounted on a supporting stud 65. The idler gear 64 meshes with a gear 65 which is keyed to a rotatable shaft 67. The shaft 67 is rotatably journaled in anti-friction bearings 66 and 69 both of which are supported by the housing 43. The upper end of the shaft 67 is provided with a gear 70 which meshes with an internal ring gear 71 which is fixedly mounted on a downwardly extending portion of the spider 53. It will be readily apparent from the foregoing disclosure that a rotary motion of the shaft 60 will be imparted through the worm 61, the worm gear 62, the gear 63, the idler gear 64, the gear 66, the shaft 67, the gear 70, and the internal ring gear 71 to impart a rotary motion to the spider 53 and the ring gear 52. The driving mechanism above described may be arranged to rotate the gear 50 and the ring gear 52 either in the same or opposite directions and at different speeds, depending upon the gear ratios employed for driving the same. It will be readily apparent from the foregoing disclosure that by relatively rotating the gears 50 and 52, a combined rotary and revolving motion will be imparted to the work holders 45, 46, 47 and 48.

In order to prevent excessive wear on the ring gear 52 and the gear 50 due to continuous rotating and revolving movements of the work holders, it is desirable to impart a relative reciprocating movement between the work holders and the driving gears 50 and 52 so that the wear on the driving gears is distributed over substantially the entire area of the gear teeth. In the preferred construction, this reciprocatory motion is obtained by imparting a reciprocatory motion to the lower lapping wheel in a manner to be hereinafter described. The reciprocating mechanism preferably comprises a hydraulically operated mechanism including a fluid pump 75 which is formed in a housing 76. The housing 76 is preferably provided with a strap portion 77 which surrounds an eccentric 78 which is fixedly supported on the lower end of the shaft 67. The pump plunger or piston 79 is fixedly supported on a collar 80 which is in turn supported on a bushing 81 which is fixedly mounted relative to the gear 63 and worm gear 62. It will be readily apparent from the foregoing disclosure that when the shaft 51 is rotated by the driving mechanism above described, it will impart a rotary motion to the eccentric 78 which in turn imparts a reciprocatory motion to the pump housing 76.

A fluid reservoir 82 is provided within a box-like section of the base 10 so that oil or other operating fluid may be contained therein to a sufficient level so that the entire pump housing 76 is immersed within the fluid. Fluid is pumped from the reservoir 82 through an intake port 83 and passes around a ball check valve 84, due to action of the pump cylinder 75 reciprocating relative to its piston 79. Fluid from a pump chamber 85 is forced through a ball check valve 86, flexible pipe 87, to a control valve 88.

In the position of the valve 88 shown in Fig. 1, fluid from the pipe 87 passes through a port 89 into a valve chamber 90 and passes through a central aperture 91 in the valve 88 into a cylinder chamber 92 formed within the housing 43. When fluid under pressure is admitted into the cylinder chamber 92, the lower end of the sleeve 41 and the bearing bushing 57 serves as a piston to raise the spider 40 and the lower lapping wheel 11 and the

work holders 45, 46, 47 and 48. The upward movement of the lapping wheel 11 is transmitted through the work pieces to raise the upper lapping wheel 12 so that both wheels are maintained in operative lapping contact with the work pieces during the reciprocatory movement. A pressure relief valve 93 is provided in the pipe 87 by means of which excess fluid under pressure within the system may be by-passed directly to the reservoir 81.

The valve 88 may be actuated by means of a bell crank lever 94 which is pivotally supported on a stud 95, the stud 95 being fixed relative to the base 10 of the machine. The downwardly extending portion of the bell crank lever rides in a groove 96 formed in the right-hand end of the valve 88. A horizontally extending portion of the bell crank lever 94 is provided with a rounded end 97 which rides in a clearance slot 98 formed in the lower end of a connecting link or rod 99. The rod 99 is fixedly connected by a stud 100 with the sleeve 41.

A load and fire mechanism is provided comprising an arrow-pointed projection 101 formed integral with the bell crank lever 94 which coacts with a spring-pressed arrow-pointed plunger 102 which is supported in the housing 43. The load and fire mechanism above described serves quickly to shift the valve 88 into a reverse position after the upper lapping wheel 12 and lower lapping wheel 11 have been raised to the desired position.

When the valve 88 is shifted toward the left to cut off the passage of fluid under pressure into the cylinder chamber 92, a port 103 is opened so that the weight of the upper lapping wheel 12 and the lower lapping wheel 11 together with its supporting mechanism may force fluid from the cylinder chamber 92 through the valve passage 91 and out through a port 103 into the reservoir 82. In order to control the downward stroke of the lapping wheels 11 and 12 and the work holders 45, 46, 47 and 48 relative to the cage driving gears, an adjustable throttle valve 104 may be provided, by means of which the exhaust of fluid from the cylinder chamber 92 may be readily controlled so that the rate of downward motion may be regulated and controlled.

It will be readily apparent that the upward movement of the lapping wheels 11 and 12 relative to the cage driving gears 50 and 52 is a slow intermittent motion caused by a small shot of oil being forced from the pump chamber 85 into the cylinder 92 each time the eccentric 78 causes a reciprocating stroke of the pump housing 76.

In the position of the parts shown in Fig. 1, the upward movement of the lapping wheels 11 and 12 will continue intermittently until the lower face of the slot 98 engages the rounded end 97 of the bell crank lever 94 and rocks the bell crank lever 94 in a clockwise direction so as to shift the valve 88 toward the left (Fig. 2). The movement of the valve 88 is controlled at first by the upward movement of the sleeve 41 until the arrow point 101 passes by the high point of the spring-pressed arrow point 102, after which the released compression of the arrow point 102 rapidly shifts the valve 88 through its remaining stroke toward the left to cut off fluid under pressure passing through the port 89, and to open the port 103 so that a downward stroke of the lapping wheels may be initiated. The downward movement of the lapping wheels 11 and 12 together with the work holders 45, 46, 47 and 48 continues until the upper end of the elongated slot 98

engages the rounded end 97 of the bell crank lever to rock the bell crank lever in a counterclockwise direction. Movement of the lever 94 in a clockwise direction serves to shift the valve 88 into the position illustrated in Fig. 1 to again initiate an upward stroke of the parts.

I have shown four work holders 45, 46, 47 and 48 in operative position in Fig. 3. It should be understood that any number of work holders may be used, that is, two, three, four or five, which can be symmetrically positioned with their gear teeth meshing with the center gear 50 and the ring gear 52.

The operation of this improved lapping machine will be readily apparent from the foregoing disclosure. In a loading position, the upper lap 12 is raised by turning the spoked, manually operable wheel 22 in a counterclockwise direction (Fig. 2) to separate the lap 12 from the lap 11, and the arm 15 may then be swung about the column 16 so that the work holders may be readily loaded into the machine. The geared work holders 45, 46, 47 and 48 are then inserted so that they mesh with both the center gear 50 and the ring gear 52. The work pieces to be lapped are then inserted in the apertures 49 formed in the work holders. The upper lap 12 may then be swung into an operative position and lowered by releasing the pawl 25 and manually turning the spoked wheel 22 to lower the upper lapping wheel 12 into operative engagement with the upper surfaces of the work piece to be lapped. The machine may then be started and the shaft 60 rotated simultaneously to impart a relative rotary motion to the gear 50 and the ring gear 52 so as to impart a combined rotary and revolving movement to the work holders 45, 46, 47 and 48. This movement carries the work pieces to be lapped through an irregular path between the opposed faces of the lapping wheels 11 and 12. During this lapping operation, a relative axial reciprocating motion is imparted between the work holders 45, 46, 47 and 48 and the work holder driving the gears 50 and 52 by means of the fluid pressure operated mechanism above described. As the eccentric 78 is rotated by the gear 66, a reciprocating motion is imparted to the pump housing 76 which serves to draw fluid from the reservoir 82 through the port 83 and ball check valve 84 into the pump chamber 85 during the movement of the pump housing in one direction, and to force fluid from the pump chamber 85 through the ball check valve 84 into the pump chamber 85 during the movement of the pump housing in one direction, and to force fluid from the pump chamber 85 through the ball check valve 85 into the cylinder chamber 92 when the pump housing is moved in the opposite direction so as to intermittently cause a vertical motion of the sleeve 41 to raise the lower lap 11 together with the work holders 45, 46, 47 and 48 supported thereby relative to the center gear 50 and the ring gear 51. This upward movement of the work holders continues until the bell crank lever 94 actuated by the upward movement of the sleeve 41 shifts the valve 88 so as to cut off admission of fluid under pressure to the chamber 92. After the valve has been shifted into its left-hand position (Fig. 1), fluid may then exhaust from the chamber 92 through the passage 91, through the port 103 and the throttle valve 104, into the reservoir 82. The weight of the spindle 41 and the lapping wheel 11 serves to force fluid from the chamber 92. By manipulation of the throttle valve 104, the rate

of downward movement of the work holders 45, 46, 47 and 48 may be readily controlled. The downward movement of the parts continues until the bell crank lever 94 is again rocked into the position shown in Fig. 1 so as again to admit fluid under pressure to the chamber 92 to initiate an upward movement of the parts. It will thus be seen that during the lapping operation, a continuous reciprocating motion is imparted to cause a relative reciprocating motion between the work holders and the gears for driving the same so as to distribute the wear between the gear teeth.

It will thus be seen that there has been provided by this invention apparatus in which the various objects hereinbefore set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a lapping machine having a pair of opposed lapping wheels, a plurality of externally geared work holders between said wheels, a work holder driving mechanism including a center gear and a ring gear each of which mesh with teeth on said holders, means relatively to rotate said gears to impart a combined rotating and revolving movement to said holders, and means to impart a relative axial reciprocation between said work holders and said work holder driving gears during a lapping operation.

2. In a lapping machine having a pair of opposed lapping wheels, a gear at the center of said wheels, a gear concentric with said pinion gear and surrounding said wheels, a plurality of external geared work holders between said wheels which mesh with said pinion gear and said ring gear, means relatively to rotate said pinion gear and ring gear to impart a combined rotating and revolving movement to said work holders, and means to impart a relative axial reciprocation between said work holders and said pinion and ring gears during a lapping operation.

3. In a lapping machine having a pair of opposed lapping wheels, a relatively thick gear at the center of said wheels, a relatively thick ring gear concentric with said pinion gear and surrounding said wheels, a plurality of relatively thin externally geared work holders between said wheels which mesh with said pinion gear and said ring gear, each of said work holders having a plurality of work receiving apertures, means relatively to rotate said pinion gear and said ring gear to impart a combined rotating and revolving movement to said work holders, and means to impart a relative axial reciprocation between said holders and said pinion and ring gears during a lapping operation so as to distribute the wear therebetween.

4. In a lapping machine having a pair of opposed lapping wheels, a gear at the center of said wheels, a ring gear concentric with said pinion gear and surrounding said wheels, a plurality of externally geared work holders between said wheels which mesh with said pinion gear and said ring gear, each of said work holders having a plurality of work receiving apertures, means relatively to rotate said pinion gear and said ring gear to impart a combined rotating and revolving movement to said work holders, and means including a fluid pressure piston and cylinder to impart a relative axial movement between said work holders and said work holder driving gears.

5. In a lapping machine a pair of opposed lapping wheels, a gear at the center of said wheels, a ring gear concentric with said pinion gear and surrounding said wheels, a plurality of externally geared work holders between said wheels which mesh with said pinion gear and said ring gear, means relatively to rotate said pinion gear and said ring gear to impart a combined rotating and revolving movement between said work holders, and means including a fluid pressure piston and cylinder to impart an axial reciprocatory movement to said work holders relative to said work holder driving gears.

6. In a lapping machine having a pair of opposed lapping wheels, an axially movable spindle to support one of said lapping wheels, a plurality of work holders between said wheels, a work holder driving mechanism including a center gear and a ring gear each of which mesh with gear teeth formed on said work holders, means relatively to rotate said gear and ring gear to impart a combined rotary and revolving movement to said work holders, and means axially to reciprocate said spindle and the lower lapping wheel so as to impart a reciprocatory movement to said work holders relative to the work holder drive gears.

7. In a lapping machine as claimed in claim 6, the combination with the parts and features therein specified, of a fluid pressure operated reciprocating mechanism for said spindle including a piston and cylinder, the end of said spindle serving as a piston, and a fluid pressure system to control the admission to and exhaust of fluid from said cylinder so as to impart a reciprocatory movement to said spindle, lapping wheel and work holders.

8. In a lapping machine as claimed in claim 6, the combination with the parts and features therein specified, of a fluid pressure operated spindle reciprocating mechanism including a piston and cylinder, said spindle serving as a piston, a self-contained fluid pressure system including a fluid pump which is actuated by said work holder driving mechanism, and means including a valve which is actuated by axial movement of said spindle to control the admission to and exhaust of fluid from said cylinder so as to impart a reciprocatory movement to said work holders relative to the work holder driving gears.

HERBERT S. INDGE.
